UNITED STATES PATENT OFFICE.

JUSTUS DOERING, OF PHILADELPHIA, PENNSYLVANIA.

DROP-BOX MECHANISM FOR LOOMS.

SPECIFICATION forming part of Letters Patent No. 225,115, dated March 2, 1880.

Application filed December 8, 1879.

To all whom it may concern:

Be it known that I, JUSTUS DOERING, of Philadelphia, Pennsylvania, have invented a new and useful Improvement in Drop-Box-Operating Mechanisms for Looms, of which the following is a specification.

The object of my invention is to construct a compact and smoothly-working device whereby the drop-boxes of a loom can be rapidly and accurately adjusted and held in position after adjustment.

The invention consists of the combination of a slide carrying a block connected to the drop-boxes and having certain spring-fingers with a series of studs and devices for operating the same, whereby the vertical reciprocation of the block and drop-boxes is effected on the longitudinal reciprocation of the slide.

The invention further consists of the combination of the slide having a swinging bar with a crank-pin, a sliding strip, and devices for operating the said pin and strip, whereby the reciprocation of the slide at the proper intervals only is effected.

The invention further consists of the combination of the studs for acting in conjunction with the fingers of the block with certain plates, pins, shafts, and arms, whereby the retraction of one stud is assured on the advancement of another, all as hereinafter fully set forth.

In the accompanying drawings, Figure 1, Sheet 1, is an end view of part of a loom, showing the application of my improved drop-box-operating device thereto; Fig. 2, a front view of part of Fig. 1; Fig. 3, Sheet 2, a longitudinal section on the line 1 2, Fig. 2, drawn to an enlarged scale; Fig. 4, a transverse section of Fig. 3 on the line 3 4; Fig. 5, Sheet 3, a sectional plan on the line 5 6, Fig. 3; Fig. 6, a plan view of part of Fig. 3; Fig. 7, a section on the line 7 8, Fig. 5; and Figs. 8, 9, and 10, reduced sections of Fig. 7 on the lines 9 10, 11 12, and 13 14, respectively.

A is a frame bolted or otherwise secured to the foundation of the loom, and constructed for the guidance of a slide, B, the reciprocation of which at the proper times is effected by means of a crank-pin, a, on a pinion, b, carried by the said frame A, the pin acting on one end of the slide B and on a bar, d, which is hung to the said slide by means of hinged

plates c, and is acted upon by a spring, c'. The slide B is only reciprocated when it is necessary to raise or lower the drop-boxes, the 55 bar d at other times being thrown out of the path of the crank-pin a by the inclined end of a strip, e, adapted to guides on the top of the frame A, the strip being held in the position shown in Fig. 6 by a latch, e', hung to the 60 strip and adapted to a recess in the frame A. The latch e' is, however, provided with a cord, e², one end of which is connected to a pin on the strip e, the other end passing through an eye on the frame A, so that on pulling said 65 cord the first effect will be to elevate the latch e', and then to draw the strip e in the direction of the arrow, Fig. 6, and thereby permit the bar d, under the influence of the spring c', to move into the path of the crank-pin a. 70

The pinion b and its crank-pin a turn in the direction of the arrow, Fig. 3, one revolution of the crank-pin being sufficient to impart a forward and backward movement to the slide B, the pin entering the slot between the bar d 75 and the end of the slide, and acting first on the said bar d, so as to move the slide forward in the direction of the arrow, and then on the end d' of said slide, so as to restore it to its original position. 80

On the forward movement of the slide B a plate, h, on the latter acts on a pin, h', on the strip e, so as to restore said strip to the position shown in Fig. 6, and thereby throw the bar d out of the path of the crank-pin a until 85 the strip is again operated.

In order to effect the reciprocation of the slide B with the proper rapidity, the pinion b is driven by a larger pinion, f, and the latter by a pinion on the driving-shaft of the loom, 90 (see Fig. 1,) the pinion b preferably making two revolutions to each revolution of the driving-shaft. In order, however, to prevent the operation of the slide B when the other parts of the loom are not in the proper positions, the 95 pinion f is furnished with a cam, f', which acts on the enlarged head, f² of the bar d, and throws the said bar out of the path of the crank-pin a until the proper time for the changing of the drop-boxes. 100

The movement of the strip e might be so timed that the cam f' on the pinion f could be dispensed with; but it is preferable to connect the cord e², which operates the strip e, to

one of the needles of the Jacquard apparatus, as shown in Fig. 1, for instance, and in this case the needle is retracted simultaneously with the opening of the shed, so that in the 5 absence of the cam f' the slide B might be operated and the boxes changed while the shuttle was being thrown.

The means whereby the longitudinal reciprocation of the slide B is caused to effect the 10 vertical movement of the drop-boxes are shown in Figs. 1, 2, 3, and 4, and are as follows: To suitable guides in the slide B is adapted a block, D, the upper end of which is connected by a link, E, to one arm of a lever, F, hung 15 to the frame of the loom, the other arm of said lever being connected by a rod, F', to an arm, F', from which is hung, by means of rods G, (only one of which is shown,) the frame J, carrying the drop-boxes, said frame being adapted 20 to suitable guides on the swinging lay M. In one side of the block D is formed a recess, i, the sides of which are partly parallel and partly flaring, so as to impart to the recess the Y shape shown in Fig. 3. In the flaring 25 portion of this recess are arranged a series of pivoted fingers, the number of which will depend upon the number of drop-boxes employed in the loom. The device shown in the drawings is adapted for operating three boxes, 30 and there are four fingers, m , m' , m^2 , and m^3 .

When the parts are in the position shown in Fig. 3 the adjacent faces of the fingers m m' form continuations of the parallel sides of the recess i, and the finger m^2 occupies an inclined 35 position midway, or thereabout, between the finger m and the upper inclined side of the recess i, the end of the finger m bearing against the end of the finger m^2 , and the latter bearing against the said inclined side of the recess. 40 The finger m^3 occupies a similar position in respect to the finger m' and the lower inclined side of the recess i.

The fingers are such that openings n are formed between the fingers m and m^2 , between 45 the fingers m' and m^3 , and between said fingers m^2 and m^3 and the inclined sides of the recess i.

A spiral spring, p, acts on the fingers m m' and tends to maintain all of the fingers in the 50 positions shown in Fig. 3, but permits either 50 of said fingers to yield under the circumstances described hereinafter.

At one side of the frame A is a casing, N, the opposite sides of which are slotted, so as to form guides for a series of plates, P, three 55 of which are shown in the present instance, one for each drop-box. The front ends of these plates are provided with studs s, which, in connection with the fingers m m' , &c., effect the vertical reciprocation of the block D and the 60 drop-boxes on the longitudinal reciprocation of the slide B, as follows: When the parts are in the position shown in Fig. 3—that is to say, with the slide D lowered to its full extent and the stud s of the lowermost plate P occupying 65 a position between the fingers m m' —the partial elevation of the block D may be effected by retracting the lower plate P and

its stud and advancing the middle plate, P', so that its stud s shall occupy a position in the opening n between the fingers m and m^2 . 70 On the forward movement of the slide B the said stud will act on the inclined face of the finger m^2 and effect the raising of the block D and the operation of the drop-box frame, the finger m yielding in order to allow the stud s to pass into the parallel portion of the recess i, and then resuming its former position, so that on the backward movement of the slide B the stud will occupy a position between the fingers m and m' , and the block D and drop-boxes will be firmly locked in position. 75

The block D may be elevated to the full extent by moving the stud of the uppermost plate P into the opening between the finger m^2 and the upper inclined edge of the recess i; 80 or the block D, when elevated, may be depressed to the extent of one box by withdrawing the uppermost plate P and advancing the middle plate so that its stud s will occupy a position between the fingers m' and m^3 , the full 85 depression of the block being effected by the co-operation of the stud s of the lowermost plate P with the finger m^3 , and the lower inclined edge of the recess i.

As an additional means of locking the block 90 D in position, said block is provided with a lug, y, which is adapted to recesses in a standard, T, on the upper edge of the frame A.

Each of the plates P has a central elongated slot, to which are adapted three vertical shafts, 100 S, the ends of which are fitted to bearings in the top and bottom of the casing N. Each of these shafts has three arms, x, which engage with pins w on the plates P, the pins and studs being so arranged in respect to each 105 other that but one stud at a time can occupy an advanced position between the fingers, the advancement of either of the other studs insuring the retraction of the stud previously advanced. This will be understood on reference to the diagrams, Figs. 8, 9, and 10.

Each of the plates P has a pin, t, to which is attached a cord, t', wound round a drum, t², carried by a shaft or spindle projecting from one side of the casing N, and each of said 115 spindles carries a drum, v, around which is wound a cord, v', one end of which is carried upward through an eye in a plate, v², while the other end extends downward and is connected to a spring-plate, v³. The upper ends 120 of the cords v' are, by preference, connected to the cords of the Jacquard apparatus, as shown in Fig. 1, for instance, and the drums v and t² are combined with suitable pawl-and-ratchet mechanism, so that the movement of 125 the drum v, caused by the elevation of the cord v', will not affect the drum t², the reverse movement of the drum v, caused by the recoil of the spring-plate v³, however, being imparted to the drum t², so as to wind the cord 130 t' thereon and effect the advancement of the plate P, to which said cord is connected.

The object of using the spring-plate v³ instead of operating the plates P directly by the

jacquard is to prevent the advancement of the plates at a time when the other parts of the loom are not in the proper positions for a change of the drop-boxes.

5 In carrying out my invention it is not necessary that the devices shown for operating the studs *s* and the strip *e* should be used in all cases. For instance, the said studs and the strip might be operated by cams or a pattern-chain, or the strip *e* and the bar *d* might be dispensed with altogether, and the slide *B* reciprocated continuously from some moving part of the loom, the use of the strip and bar, however, being preferred, as it obviates the 10 excessive wear which would be caused by a continuous reciprocation of the slide *B*.

The means for connecting the drop-box frame to the block *D* will, of course, be varied as the character of the loom to which the operating 15 mechanism is applied may suggest.

I claim as my invention—

1. The combination of the slide *B*, devices for guiding and reciprocating the same, the guided block *D*, having spring-fingers, as described, the drop-box frame *J*, devices for connecting said frame to the block *D*, the studs *s*, and devices for advancing and retracting said studs, all substantially as set forth.

2. The combination of the slide *B*, devices for guiding and reciprocating the same, the guided block *D*, having a recess, *i*, and spring-

fingers located therein, as described, the drop-box frame *J*, devices for connecting said frame to the block *D*, the studs *s*, and devices for advancing and retracting said studs, as set forth.

3. The combination of the frame *A*, the slide *B*, having a swinging bar, *d*, the crank-pin *a*, devices for rotating the same, the strip *e*, with inclined end, and means, substantially as described, for adjusting said strip.

4. The combination of the frame *A*, the slide *B*, having a swinging bar, *d*, and spring *c'* for acting thereon, the pinion *b*, having a crank-pin, *a*, the pinion *f*, having a cam, *f'*, the strip *e*, having an inclined end, and devices for rotating said pinion *f* and operating the strip *e*, as set forth.

5. The combination of the casing *N*, the slotted plates *P*, having studs *s* and pins *w*, and the shafts *S*, having arms *x*, said arms *x* and pins *w* being arranged as described, whereby the advancement of one plate effects the retraction of the plate previously advanced, as set forth.

In testimony whereof I have signed my name to this specification in the presence of two subscribing witnesses.

JUSTUS DOERING.
